UNITED STATES PATENT OFFICE

CLOVIS E. CLARKE AND CARLYSLE H. CLARKE, OF RICHMOND, VIRGINIA

DESIGN FOR A CHAIR

Application filed May 25, 1931. Serial No. 39,968. Term of patent 14 years.

To all whom it may concern:

Be it known that we CLOVIS E. CLARKE and CARLYSLE H. CLARKE, citizens of the United States, residing in the city of Richmond and State of Virginia, have invented a new, original, and ornamental Design for a Chair, of which the following is a specification, reference being had to the accompanying drawings, forming part thereof, in which—Fig. 1 is a side view of the article, showing our new design; Fig. 2 a top plan view; Fig. 3 a front view, and Fig. 4 a rear view.

We claim:

The ornamental design for a chair, as shown.

In testimony whereof we have hereunto set our names this 21st day of May, 1931.

CLOVIS E. CLARKE.
